DISPENSING VALVE

Leonard M. Collins, Los Angeles, Calif., assignor to Pressure Dispensers, Inc., Hollywood, Calif., a corporation of California

Filed Mar. 12, 1958, Ser. No. 720,936
6 Claims. (Cl. 222—553)

This invention relates generally to dispensing valves and relates especially to dispensing valves for use with pour, shake or squeeze containers or bottles adapted to dispense finely divided solids and/or fluids.

The conventional fluid or solids dispensing means usually consists of an internally threaded cap adapted to be mounted onto a threaded neck or spout of a bottle or container. Such dispensing means has the disadvantage that the cap must be completely detached from the container in order to dispense the contents therefrom, which leads to a second disadvantage, that of losing or misplacing the cap. Further, the conventional screw-on cap is generally not constructed so as to effect a leak-proof seal.

Some one-piece dispensing caps, known in the prior art, need not be detached from the bottle when dispensing fluids or solids, but, in general, these one-piece caps also do not effect a leak-proof seal with the container.

In the prior art, dispensing caps are known which are not required to be detached for dispensing fluids or granular solids and are leak-proof; however, these caps are unduly complicated in structure and therefore expensive, this type of dispensing cap or valve being generally constructed with at least two distinct elements or parts.

Bearing in mind the foregoing facts, it is a major object of the present invention to provide a dispensing valve, for dispensing fluids and granular solids, that is not required to be detached during the dispensing operation and which is extremely simple in structure and inexpensive to manufacture.

It is another major object of the present invention to provide a one-piece dispensing valve or cap for dispensing fluids and granular solids which is extremely simple in structure, and which is leakproof.

A further object of the present invention is to provide a one-piece dispensing valve which need not be detached from the container during the dispensing operation, and which effects a leak-proof seal with the container.

These and other objects and advantages of the invention will be more clearly understood by reference to the following description and to the accompanying drawings, in which:

FIGURE 1 is a perspective view of my dispensing cap or valve mounted on a fluid or granular solids container;

FIGURE 2 is an assembled axial cross-sectional view in elevation along the line 2—2 of FIGURE 1 of my dispensing cap or valve and container, shown in open dispensing position;

FIGURE 3 is a cross-sectional view, in plan, of my dispensing cap and container therefor, along the line 3—3 of FIGURE 2 but shown in open dispensing position;

FIGURE 4 is a cross-sectional view, in plan, of my dispensing cap and container therefor, along the line 4—4 of FIGURE 2, shown in closed non-dispensing position;

FIGURE 5 is an exploded axial cross-sectional view, in elevation, along the line 2—2 of FIGURE 1 of the neck of the container and of my dispensing cap;

2

FIGURE 6 is a fragmentary axial cross-sectional view in elevation, of a modified form of my dispensing cap showing an automatic indexing means; and

FIGURE 7 is a cross-sectional view, in plan, along the line 7—7 of FIGURE 6.

The dispensing cap or valve of my invention is a unitary structure and is preferably made of a slightly deformable chemically resistant plastic, such as polyethylene. The cap is preferably molded in the forms to be described, by conventional molding methods.

Referring now to FIGURES 1, 2 and 5 especially, my novel dispenser cap or valve is designated generally by the numeral 10 and comprises an outer generally cylindrical housing 12 to one end of which is, preferably integrally, affixed a nozzle 14. The nozzle 14 comprises a nozzle tip 16, having an outlet passage 18 formed therein, and an annular nozzle shoulder 20 preferably integrally affixed to the nozzle tip 16 as well as being affixed to one end of the housing 12. The nozzle 14 is thus integrally affixed to the housing 12, and forms one end thereof.

A generally hollowed-out inner cylinder 22 is preferably integrally affixed to the inner wall 24 of the nozzle shoulder 20, the longitudinal axes of both cylinder 22 and housing 12 being parallel. The cylinder 22 is spaced from the inner wall 26 of the housing 12 to thus form a cylindrical channel 28 (see FIGURE 5).

The spout or neck 30 of any conventional container 32, to which my dispensing cap 10 is to be permanently affixed, is generally cylindrical in shape and has a diameter substantially equal to the diameter of channel 28. An annular bead or rib 34 is preferably integrally molded to the upper end of the spout 30 for sealing purposes, as will be described.

In order to permanently assemble the cap 10 onto the container 32 it is necessary only to place the cap 10 onto the cylindrical spout 30 so that the channel 28 of the cap 10 is in alignment with the wall 38 of the cylindrical spout and then force the cap 10 towards the base 40 of the spout 30. In so doing, the annular bead 34 which is made of a resiliently deformable material, such as plastic, is compressed, as it rides within the plastic-walled resiliently deformable channel 28. The bead 34 is expanded to its normal size as it is seated within a complementary space 42 formed, or molded, just below the nozzle shoulder 20 in the interior of the housing wall 12. In this manner, a leak-proof seal between the container spout 30 and the cap 10 is effected.

It will be noted that the housing wall 12 is enlarged at 44 to thereby act as a reinforcing means in the region of the enlarged annular space.

The inner hollowed-out cylinder 22 has, preferably integrally, mounted thereto an inner channel housing 45 in which an outlet conduit passage 46 is formed, one end 55 of the outlet passage 46 communicating with the outlet passage 18 formed in the nozzle tip 16 and the other end communicating with the cylindrical channel 28 (see especially FIGURES 2 and 5).

It will be noted that an arrow 50, molded onto the cap 10, is in axial alignment with the outlet conduit passages 46 and 18 and that an arrow or index 52, molded onto the container 32, is in axial alignment with an inlet passage or groove 36 formed in the wall 38 of the container 32. The groove 36 is shown somewhat enlarged for purposes of illustration.

60

As the cap 10 is initially seated on the bead 34 of the spout 30 during assembly, the indexing means or arrows 50 and 52 respectively area, preferably positioned, out of alignment. As best shown in FIGURE 4, it will be seen that there can be no communication between the inlet passage 36 and the outlet passages 46 and 18. However, as the dispensing cap 10 is rotated about the spout 30 so that the arrow 50 coincides with the arrow 52, the inlet passage 36 is sufficiently long to be placed into communication with the outlet passage 46, as best shown in FIGURES 2 and 3, the inlet passage 36 or groove running approximately one-half the longitudinal distance of the neck 30. Thus, it will be seen that by merely rotating the dispensing cap 10 to a point of indexing alignment, fluids or granular solids may be dispensed from container 32. The container 32 may be a plastic squeeze bottle, a glass bottle, or other conventional material. The on or off position of the dispensing cap 10 is readily obtained by a glance at the arrows 50 or 52 to ascertain whether they are, or are not, in alignment.

In addition to the aforementioned sealing action effected by the bead 34 in its seat or space 42, another seal is effected by the tight engagement of the walls of the spout 30 with the walls defining the cylindrical channel 28 above the level of the inlet passage or groove 36. This sealing effect is best shown in FIGURE 2, wall 38 of the spout 30 tightly interfitting between cylinder 22 and housing 12 and cooperating with the bead 34 tightly fitting within annular recess 42 to insure a leak-proof joint when the cap 10 lies in the open position of FIGURES 2 and 3, or in the closed position of FIGURE 4.

The bead 34, once firmly seated, also firmly retains the cap 10 from movement in the direction of its longitudinal axis. Attention is also drawn to the fact that an extremely small quantity of plastic material is necessary to make the cap 10.

The indexing means 50 and 52 previously described, requires visual attention inasmuch as the coincidence or non-coincidence of several arrows must be noted. An automatic indexing means not requiring visual attention, or attention of any sort, is shown in FIGURES 6 and 7. Generally the automatic on-off indexing means comprises a projecting stop 60 formed or molded onto the spout 30 and cooperating with a guide or groove 62 formed in the housing 12. As the stop 60 abuts one end of the groove 62 further relative movement of the cap 10 and spout 30 is prevented, and the inlet and outlet passages 36 and 46 respectively will automatically not be in communication, as best shown in FIGURE 7. As the cap 10 is rotated clockwise approximately 90° of arc, the stop 60 abuts the opposite ends of guide 62 and automatically aligns inlet passage 36 with outlet passages 46 and 18.

Attention is drawn to the fact that in both embodiments of the invention described herein, several inlet passages, equivalent to the structure of inlet passage 36, may be employed, especially where more viscous fluids are to be dispensed. Also, it will be seen that where the outlet passages 46 and 18 form a right angle, different configurations could be used, as for example, an inclined outlet passage.

While several embodiments of my invention have been shown and described, it will be apparent, to thoses skilled in the art to which this invention pertains, that changes and modifications may be within the scope of the invention. I therefore intend to be limited only to the following claims.

In a further modification, a portion of the exterior surface of the cap 10 may be knurled, as for example, in an annular configuration about the center of the cap, the knurled band enabling one to readily rotate the cap to a desired position.

I claim:

1. In combination, a dispensing valve and a container therefor having an outlet spout which comprises: a dispensing valve housing having a first and a second end; means defining with the interior of said housing a generally annular channel commencing at said first end and running parallel to the longitudinal axis of said housing to approximately said second end thereof, said channel being slightly enlarged near said second end; means defining an outlet passage in communication with said generally annular channel, and passing through said housing, said container outlet spout being adapted to rotatably and slidably engage the walls defining said channel and having an enlarged resiliently deformable bead at one end thereof which is generally complementary to the enlargement in said channel whereby to prevent axial displacement of said valve from said spout and to prevent leakage from said container, said container spout having an inlet passage formed in the wall thereof communicating with the interior of said container, said inlet passage communicating with said outlet passage, through a portion of said annular channel upon rotation of said dispensing valve housing to a given position and being sealed from said outlet passage means upon rotation of said dispensing valve housing less than 360° from said given position.
2. The apparatus of claim 1 wherein said valve and said spout each have indexing stops affixed thereto adapted to prevent relative rotational movement as the valve and spout outlet and inlet passages are aligned for dispensing and for sealing.
3. The apparatus of claim 1 wherein said housing is reinforced in the region of said channel enlargement.
4. In combination, a dispensing valve and a container therefor having an outlet spout which comprises: a dispensing valve housing; means defining with the interior of said housing a generally cylindrical channel, said channel being slightly enlarged near one end thereof; means defining an outlet passage in communication with said generally cylindrical channel, and passing through said housing, said container outlet spout being adapted to rotatably and slidably engage the walls defining said channel and having an enlarged bead at one end thereof which is complementary to the enlargement in said channel whereby to prevent axial displacement of said valve from said spout and to prevent leakage from said container, said container spout having an inlet passage formed in the wall thereof communicating with the interior of said container, said inlet passage communicating with said outlet passage upon rotation of said dispensing valve housing to a given position and being sealed from said outlet passage means upon rotation of said dispensing valve housing less than 360° from said given position.
5. A dispensing valve, for a container having an outlet spout, an enlarged bead on the end of said outlet spout and an inlet passage in said outlet spout communicating with the interior of said container, which comprises: a housing defining therewithin a flow channel, said flow channel being enlarged at one end thereof and complementary with the enlarged bead of said outlet spout, said housing being adapted to be rotatably engageable with said outlet spout, and the enlargement of said channel being adapted to be rotatably engageable with said complementary enlarged bead on said outlet spout but preventing vertical displacement of said valve from said spout and preventing leakage from said container; and means defining an outlet passage in communication with said flow channel, and passing through said housing, the inlet passage of said outlet spout communicating with said outlet passage, through said flow channel, upon rotation of said dispensing valve to a given position, and being sealed from said outlet passage upon rotation of said valve less than 360° from said given position.
6. In a container having an outlet spout, a rounded

bead on the periphery of said outlet spout and an inlet passage in said outlet spout communicating with the interior of said container, an improved dispensing valve, rotatable to a dispensing and to a nondispensing position, which comprises: a housing defining therewithin a flow channel, said flow channel being enlarged at one end thereof and complementary with the rounded bead of said outlet spout, said housing being adapted to be rotatably engageable with said outlet spout, and the enlargement of said channel being adapted to be rotatably engageable with said complementary rounded bead on said outlet spout but preventing vertical displacement of said valve from said spout and preventing leakage from said container; and means defining an outlet passage in communication with said flow channel, and passing through said housing, the inlet passage of said outlet spout communi-

cating with said outlet passage, through said flow channel, upon rotation of said dispensing valve to a given position, and being sealed from said outlet passage upon rotation of said valve less than 360° from said given position.
